UNITED STATES PATENT OFFICE.

THEODORE H. EICKHOFF, OF CLEVELAND, OHIO, ASSIGNOR, BY MESNE ASSIGNMENTS,
TO AUTO-ORDNANCE CORPORATION, OF NEW YORK, N. Y., A CORPORATION OF NEW
YORK.

FIREARM.

1,312,687.

Specification of Letters Patent. Patented Aug. 12, 1919.

Application filed March 20, 1918. Serial No. 223,657.

To all whom it may concern:

Be it known that I, THEODORE H. EICKHOFF, a citizen of the United States of America, and resident of Cleveland, in the county of Cuyahoga and State of Ohio, have invented new and useful Improvements in Firearms, of which the following is a specification.

This invention relates to firearms and more particularly to the firing members and associated mechanism of firearms.

Firing members for pistols, rifles, and other types of firearms employing cartridges, usually comprise elongate pins reciprocably mounted in the breech block or bolt so as to be driven forward by hammer mechanism into engagement with the primer cap of a cartridge in the firing chamber. These pins are loosely mounted in the bolt and it frequently happens that upon throwing the bolt into forward breech-closing position the momentum of the firing pin created by the forward movement of the bolt carries the firing pin into engagement with the primer cap of the cartridge in the firing chamber resulting in a premature firing of the cartridge. This is particularly likely to happen in automatic and semi-automatic guns where the breech block or breech closure is thrown forward with considerable force and rapidity. Moreover, the difficulty is not limited to reciprocating firing pins, but is incident to all firing members arranged so that their momentum tends to carry them into firing position when the bolt is moved into forward position.

It is the principal object of the present invention to overcome the aforesaid difficulties and to provide a firing member whose forward momentum does not tend to carry it into firing position. Another object is to provide a firing pin of such character that it can be disposed at the forward end of the breech bolt or other breech closure in a restricted space and in such manner that it may be actuated from one side of the breech closure by a hammer or other suitable mechanism.

The invention comprises a firing member movably mounted on the breech block of a gun so as not to be thrown into firing position by its momentum when the breech block reaches its forward position. The firing member is arranged to be oscillated into and out of firing position and is preferably

mounted to oscillate about a shaft, trunnions, or similar pivot. The means for pivotally mounting the firing member on the breech closure is arranged to engage the member either in the plane of the center of gravity of the member or between this plane and the plane of the firing point of the member. Thus when the firing member is arranged with its firing point at or near its upper end the point or line of engagement between the firing member and breech block is disposed at or above the longitudinal plane passing through the center of gravity of the firing member.

In the accompanying drawings.— 70

Figure 1 is a side elevation of a portion of a rifle with parts broken away and sectioned showing one embodiment of my invention in operative position therein;

Fig. 2 is a side elevation on a larger scale 75 of the firing member in Fig. 1;

Fig. 3 is a perspective view of the forward end of the rifle bolt showing the firing member mounted therein;

Fig. 4 is a view similar to Fig. 3 showing a modified form of my invention; and

Fig. 5 is a vertical longitudinal central section of Fig. 4 showing the modified form of locking member in side elevation.

The firearm chosen for the purpose of 85 illustrating my invention comprises a rifle having a stock 1, barrel 2, breech block or bolt 3, and a firing chamber 4 adapted to receive a cartridge 5.

The embodiment of my improved firing member illustrated in Figs. 1, 2 and 3 comprises a segmental member 6 having a firing point 8 at one end, a hammer engaging head 9 at its other end, and an opening 10 at its center for pivotally supporting the member. 90 The bolt 3 is provided with a recess 11 at its forward end to receive the firing member, a screw 12 extending across the recess through the opening 10 pivotally to support the firing member in the recess.

Thus the firing member is free to oscillate about the screw 12 which constitutes a bearing. Owing to the fact that the opening 10 is disposed near the forward end of the firing member the weight of the member tends to move the member in a clockwise direction (Figs. 1 and 2) away from the cartridge in the firing chamber. The hammer 13 controlled by the trigger 14 through the medium of suitable mechanism is dis- 110

posed beneath the head 9 on the firing member so that when it is caused to strike upwardly against the head 9 the firing member is rotated in a counter-clockwise direction (Figs. 1 and 2). The firing member is so positioned in the forward end of the bolt that the point 8 will engage the primer cap of a cartridge in the firing chamber when the firing member is rotated in a counter-clockwise direction.

A cardinal feature of the present invention consists in so mounting the firing member that its momentum will not tend to throw it into firing position when the breech bolt is thrown forwardly, and when the firing member is pivotally supported on an axis below the firing point this result is attained by disposing the center of gravity of the firing member either in the plane of the axis of the firing member which is parallel to the direction of travel of the breech bolt or at a point below this plane. Thus in Fig. 2, the line *c g* represents the plane of the center of gravity of the firing member and the line *a* represents the plane of the pivotal axis of the member.

In order to have the center of gravity fall near the bottom of the firing member the firing member may be flared laterally outwardly from top to bottom as shown in Fig. 3. When the firing member is flared outwardly in this manner the recess 11 in the bolt is preferably made wider at the bottom than at the top as shown in Fig. 3.

When the center of gravity is disposed below the longitudinal plane containing the axis of the firing member, the momentum of the firing member does not tend to throw the member into firing position when the breech bolt is moved forwardly. On the contrary, when the breech bolt is suddenly stopped at the forward end of its forward movement, the inertia of the firing member tends to rotate the firing member away from the cartridge in the firing chamber. While the firing member may be prevented from being thrown into firing position by locating the center of gravity of the member in the plane of the pivotal axis of the member I prefer to locate the center of gravity somewhat below this plane so as more certainly to avoid a premature discharge and also so as to cause the firing member to move into retracted position when the bolt reaches its forward position if the firing member has not already assumed this position.

With the firing member mounted as illustrated in Figs. 1 to 3, it is obvious that gravity tends to move the member into retracted position. However, in certain aspects of the invention the operation of the firing member may be rendered independent of the action of gravity. For example, the firing member may be mounted in a recess entering the bolt at one side so as to oscillate

about a vertical axis, in which case gravity has no effect on the firing member when the gun is in the normal horizontal position. However, when the firing member is mounted to rotate about a vertical axis the disposition of the center of gravity on the side of the longitudinal plane of the axis of the member opposite to the firing point 8 will cause the point to move away from the cartridge when the breech bolt reaches its forward position.

As further illustrating the fact that the principle of the present invention may be utilized in various ways, it is to be understood that the firing member might be mounted in the forward end of the bolt upside down with respect to the position illustrated in Figs. 1 to 3, in which case the hammer mechanism would be disposed above instead of below the bolt, and the center of gravity would be located in or above the plane containing the pivotal axis of the firing member which is disposed in parallelism with the line of travel of the bolt.

In Figs. 4 and 5 I have illustrated a modification of my invention in which the firing member 6' is inclosed in a recess 11' in the forward end of a bolt 3' by an angular member 15 so as to oscillate to and fro into and out of firing position instead of being mounted on a shaft as in Figs. 1 to 3. The member 15 may be mounted in the recess 11' in any suitable manner, and for this purpose I have shown machine screws 16. An opening 17 is left at the top of the recess 11' to permit the firing point 8 of the firing member to engage the primer cap of the cartridge in the firing chamber, and an opening 18 is left at the rear end of the recess 11' to permit the hammer head 9' of the firing member to project therethrough.

While the firing member may be loosely mounted in the recess in the forward end of the breech bolt in a number of ways according to the present invention, I prefer to arrange the member as follows: The pivotal axis of the firing member is disposed at 19 and the central portion 20 is made concentric with this axis. The upper segmental portion 21 of the member and the surface 22 of the recess with which the segmental portion contacts are also made concentric with the axis 19. Thus when the firing member 6' is oscillated to and fro the segmental portion slides along the surface 22 and the circular portion 20 rotates against the two walls of the member 15, the motion being purely rotative about the pivotal axis 19. Owing to the fact that the portion 20 of member 6' is circular and concentric with the axis 19, the portion 20 engages the front wall of member 15 along a line in the same horizontal plane with the axis 19. The center of gravity of the firing member is

therefore disposed in or below this plane according to the present invention.

This invention is particularly intended to be employed in connection with apparatus such as illustrated in the application of myself and Oscar V. Payne, Sr. No. 203,887, filed November 26, 1917 in which means for automatically actuating the bolt and locking it in firing position is associated with the rear end of the bolt in such manner as to render it impractical to employ the ordinary reciprocatory firing pin extending longitudinally through the bolt.

It will be observed that in both modifications of my invention herein disclosed, a bearing engages a forwardly directed face of the firing member intermediate the ends of the firing member and the bearing is disposed in a line which does not pass outside the center of mass of the firing member, whereby the firing member is retained in retracted position by its own inertia when the breech block is moved into firing position. This is accomplished by the division of the inertia of the firing member into two components which counteract each other, the component tending to move the firing member from firing position being at least equal to the component tending to move the firing member into firing position. Thus in Figs. 1 to 3, where the bearing for the firing member comprises a pin, the forwardly directed face of the opening 10 bears against the pin when the breech closure is shot forward; and, owing to the fact that the inertia of the portion of the firing member below the center of this face is greater than that of the portion above this center, the firing member is prevented by its own inertia from being thrown into firing position. In Figs 4 and 5 the corresponding bearing for the firing member is the front wall of the member 15 and this bearing engages the forwardly directed face 23 of the firing member at a point at or above the center of mass of the firing member so that the firing member is prevented by its own inertia from being thrown into firing position when the bolt is shot forward.

50 What I claim is:

1. In a gun having a breech block mount-

ed behind the firing chamber to move to and from the firing chamber, the combination of a firing member, and means for mounting the firing member on the breech block so that it may be oscillated into and out of firing position, said means engaging the firing member in line with its center of gravity or on the side of its center of gravity opposite to the firing point of the member so that the firing member is not thrown into firing position by its momentum when the breech block reaches its forward position.

2. In a gun having a breech block mounted behind the firing chamber to move to and from the firing chamber, the combination of an oscillatory firing member having a firing point at its upper end, and means for supporting the firing member on the breech block so as to be oscillated into and out of firing position, the supporting means being arranged to engage the firing member at or above its center of gravity so that the firing member is not thrown into firing position by its momentum when the breech block reaches its forward position.

3. In a gun having a breech block mounted behind the firing chamber to move to and from the firing chamber, the combination of a firing member, and means for pivotally supporting the firing member on the breech block, the pivotal axis of the firing member being disposed between the firing point and center of gravity of the firing member so that the firing member is not thrown into firing position by its momentum when the breech block reaches its forward position.

4. In a gun having a breech block mounted behind the firing chamber to move to and from the firing chamber, the combination of a bell-crank firing member having a firing point at one end and a hammer engaging head at the other end, and means for pivotally supporting the firing member between its firing point and its center of gravity so that the firing member is not thrown into firing position by its momentum when the breech block reaches its forward position.

Signed by me at Cleveland, Ohio, this eleventh day of March, 1918.

THEODORE H. EICKHOFF.
